UNITED STATES PATENT OFFICE

HANS KREIDEL, OF WIESBADEN, GERMANY

WICK OILER

Application filed June 7, 1929, Serial No. 369,161, and in Germany February 20, 1929.

The present invention relates to improvements in wick oilers and is more specifically concerned with the provision of a container for a supply of lubricant having an air inlet and outlet passageway and a lubricant discharge passageway in which a wick is securely positioned. Except for these openings, the container is closed and capable of sustaining high pressures.

10 One of the principal objects of my invention is to provide a container for the lubricant provided at its highest point with a valveless air inlet and outlet device, also capable of being used for a connection to a 15 lubricant pressure pump. Wick oilers of the type in which an air inlet and outlet device is provided with an automatic floating valve are more or less familiar in the art. The provision of a floating valve considerably increases the cost of production of such wick 20 oilers. In addition it is also necessary that the container for the lubricant be vertically positioned. Further, it is not always possible to completely expel the air from the lubricant 25 container. The air may also remain in the upper portion of the container and act as a resilient cushion when exposing the lubricant to pressure, thereby preventing the pressure produced by an air or lubricant pump 30 from being utilized to its fullest extent.

It is another object of this invention to provide an improved wick oiler wherein all the air in the container may be expelled, thus enabling parts connected thereto to be more 35 effectively lubricated.

It is a further object of my invention to provide an oiler having a container for oil provided with means whereby the oil may be fed to the bearing either under high pressure 40 or by capillarity at atmospheric pressure. It is the object to provide means whereby a fresh supply of oil may be forced under high pressure through the capillary ducts to clean the latter and to permit release of this 45 pressure as soon as the bearing flushing operation is completed.

Other objects and advantages will be more apparent as the description progresses, reference being had to the accompanying drawings, in which:

Fig. 1 is a vertical cross-sectional view of one type of my improved wick oiler showing a well-known type of fitting on the upper surface thereof and a coupling and a flexible hose suspended thereabove;

Fig. 2 is an elevational view of my improved wick oiler provided with push type fittings on its upper surface for engagement by the nozzle of a push type gun;

Fig. 3 is a side elevational view of a modified form of my improved wick oiler showing a horizontally arranged lubricant container; and

Fig. 4 is a cross-sectional view of a further modified form of my improved wick oiler provided with a horizontally positioned lubricant container and a push type connector for a lubricant nozzle arranged near its upper end.

In the drawing I have shown a supply 70 container *a* provided with a cover *b* screw-threadedly attached to the upper end of the container. An outlet passageway *c* extends from the bottom of the container through a screw-threaded extension *f* adapted to be 75 screw-threadedly engaged in a suitable tapped hole in a bearing to be lubricated. A suction or capillary attraction wick *d* is provided extending through the passageway *c* into the opening in the bearing to be lubricated. The wick *d* is formed at its upper end with an enlargement so that it cannot readily be pulled through the passageway *c* and this enlargement may be in the form of a knot tied in the end thereof or in any other 80 suitable manner. To prevent this knot from clogging the entrance to the passageway *c* a plurality of lateral grooves or passageways *e* are provided in the bottom wall of the container *a* extending outwardly from the lubricant 85 passageway *c*.

Referring to Fig. 1, a valveless nipple *g* is provided screw-threadedly mounted in the upper surface of cover *b*. Adjacent nipple *g* is positioned another nipple *i* which may be provided with a ball check valve *h* of a conventional type. Each of the nipples *g* and *i* are provided with locking pins *k* for suitably connecting a nozzle *l* of a lubricant 90 hose *m* thereto. The lubricant hose *m* may 100

extend from a pressure pump (not shown) or any suitable source of lubricant under pressure.

In the operation of the device shown in Fig. 1, the lubricant nozzle *l* is connected to the nipple *i* and a supply of suitable lubricant is pumped into the container *a* until it has been completely filled and lubricant passes out of the other nipple *g*. This operation forces out all the air which may have been in the container *a*. At this time lubricant will freely flow through wick *c* to the parts to be lubricated. If it is desired to force lubricant under pressure through the wick *c* to the bearing to be lubricated the container *a* may be filled as already described and after filling the container the lubricant nozzle *l* is removed from the nipple *i* and attached to nipple *g*. Lubricant under pressure now enters the container *a* through nipple *h* and, due to the fact that valve *h* effectively prevents any escape of oil through nipple *i*, a pressure will be built up and lubricant will be forced through passageway *c* under pressure. In this way the lubricant may be forced under high pressure to the bearing to be lubricated to clean and flush the latter by a copious flood of fresh oil. This operation of flushing the bearing also accomplishes a very advantageous result in cleaning the capillary ducts of the wick. After the lubricator has been in use for some time, there is a tendency for the oil to become hardened and, together with minute foreign particles, to clog the capillary passageways in the wick. Unless this deposit of foreign matter and hardening oil is periodically removed, it will eventually render the wick wholly incapable of carrying oil to the bearing. In the normal use of my improved lubricator the oil will be forced under extremely high pressures through the capillary wick itself and thereby purge the latter of the obstructions in the minute passageways thereof.

It will be noted that during the operation of supplying oil under pressure to the lubricator a connection will be made with the valveless nipple *g* so that as soon as this operation is completed the lubricator will immediately be vented to the atmosphere. Thus, even though a small volume of air should have been trapped in the lubricator, this air will not have an opportunity to force the oil through the capillary duct at greater than the desired rate of feed.

In the modification illustrated in Fig. 2 the cover *b* is provided with a nozzle engaging nipple *g* of the familiar type in which connection is made with the nozzle *n* of a lubricant gun by direct contact. In the arrangement shown in Fig. 2 lubricant is furnished to the container *a* through nozzle *n* and, if desired, lubricant under pressure may be forced through the passageway *c* by build-

ing up a pressure in container *a* through prolonged contact between the nipple *g* and nozzle *n*.

Fig. 3 illustrates a similar arrangement of nipples *g* and *i* to that shown in Fig. 1 and the lubricating operation will be similar to that of the device shown in Fig. 1, the material difference between the two being that the container *a* in Fig. 3 is formed in a horizontal manner with the valveless nipple *g* placed in the uppermost part of the container.

Correspondingly, Fig. 4 illustrates a modification of Fig. 2. The container *a* is shown as a horizontal container and the nozzle engaging nipple *g* is situated in the uppermost part of the container.

It will be apparent from the foregoing description that a simple and effective wick lubricator has been provided whereby lubricant may initially be forced to the bearings under pressure and then lubricant under atmospheric pressure will flow to the bearing to be lubricated due to the capillary attraction of the wick *d*.

It will further be apparent that an extremely simple arrangement of parts has been provided which does not detract from the effectiveness of the operation of the device.

While I have illustrated and described a single embodiment of my invention, it will be readily apparent that many changes and modifications may be made without departing from the spirit of the invention.

What I claim is new and desire to secure by Letters Patent of the United States is:

1. A wick oiler comprising a lubricant container, means on said container for making a quick detachable connection with a source of lubricant under pressure, said means being located adjacent the highest point of said container and forming a duct for free flow in both directions, means for securing said container to a part to be lubricated, said means having a passageway therein, a wick in said passageway for conducting the lubricant from said container to the part to be lubricated by capillary attraction, and a check-valve fitting for making a quick detachable connection with a source of lubricant under pressure for filling said container.

2. A wick oiler comprising a container for lubricant, a valved nipple thereon for attachment to a source of lubricant supply, said container having an outlet passageway, a capillary wick secured in said outlet passageway, and a valveless air inlet and outlet member secured to said container adjacent the top thereof, said member having means for making a quick detachable connection with a lubricant pressure supply apparatus.

3. A lubricator comprising a container for lubricant, means thereon for making a detachable connection with a source of lubricant under pressure, said container having an air

inlet and outlet passageway communicating with the top thereof, and an oil passageway for conducting oil from the container to a part to be lubricated, means associated with

5 said air passageway for making a detachable connection with a source of lubricant under pressure, and a capillary wick secured in and substantially filling said oil passageway.

4. A wick oiler comprising a lubricant container, a pair of connectors on said container for making quick detachable connections with a source of lubricant under pressure, one of said connectors being located adjacent the highest point of said container and forming 15 a duct for free flow in both directions and the other of said connectors having a passageway closed by a check valve opening to permit flow into the container and preventing flow therefrom, means for securing said container to a part to be lubricated, said means having a passageway therein forming the only path of communication between said container and a part to be lubricated, and a wick in said passageway for conducting the 20 lubricant from said container to the part to be lubricated by capillary attraction, said wick substantially filling said passageway.

In testimony whereof I affix my signature.

HANS KREIDEL.
